His Attorney.

UNITED STATES PATENT OFFICE

RUDOLPH A. BIERWIRTH, OF SCHENECTADY, NEW YORK, ASSIGNOR TO GENERAL ELECTRIC COMPANY, A CORPORATION OF NEW YORK

APPARATUS FOR AMPLIFYING ELECTRICAL ENERGY

Application filed July 12, 1927. Serial No. 205,203.

My invention relates to apparatus for amplifying electrical energy, such as that utilized in communication systems and the like, and has for its principal object the provision of an improved apparatus and method of operation which may be utilized over a wide range of audio frequencies without substantial change in the ratio of amplification.

In the operation of the transformer or impedance coupled amplifier heretofore provided, difficulty has been encountered due to the fact that the amplification ratio varies with frequency. In accordance with my invention, this difficulty is avoided by the use of a coupling element wherein a capacity and a plurality of inductances are so related to the other elements of the amplifier as to produce a substantially constant transformation ratio over a frequency range which includes low audio frequencies.

My invention will be better understood from the following description when considered in connection with the accompanying drawing and its scope will be pointed out in the appended claims.

Referring to the drawings, Fig. 1 shows an amplifying apparatus wherein my invention has been embodied; and Fig. 2 relates to the operation of the apparatus shown by Fig. 1.

$$\frac{E_{g5}}{AME_{g4}} = \frac{\omega L_7}{\sqrt{\left[R_4 \left(\frac{L_7}{L_6} + 1 - \frac{1}{\omega^2 L_6 C_8} \right) + R_7 \right]^2 + \left[\frac{R_4 R_7}{\omega L_6} - \omega L_7 + \frac{1}{\omega C_8} \right]^2}} \quad (1)$$

This apparatus comprises input terminals 1 and output terminals 2 which are interconnected through means comprising a transformer 3, space discharge devices 4 and 5, and a coupling element consisting of windings 6 and 7 and a condenser 8 connected between one terminal of the winding 6 and a terminal intermediate the ends of the winding 7 which may function as an auto-transformer. Current is supplied to the plate or anode circuits of the devices 4 and 5 from a source 9, and a suitable bias potential is applied to the grids of these devices by a source 10. With these connections, the winding 7 functions as an autotransformer, its primary cir-

cuit being connected through the condenser 8 to the plate circuit of the device 4 and its secondary circuit being included in the grid circuit of the device 5. It will be apparent that the winding 7 may be replaced by a transformer provided with separate primary and secondary circuits and that its intermediate terminal may be adjusted for the purpose of changing its transformation ratio.

In order that the amplification ratio may be maintained substantially constant over a wide range of frequencies, it is necessary that the inductances L_6 and L_7 of the windings 6 and 7 and the capacity C_8 of the condenser 8 bear a certain definite relation to the anode or plate circuit resistance R_4 of the device 4 and the primary circuit resistance R_7 of the winding 7.

When a transformer or an auto-transformer coupling is operated at low frequencies, the voltage of the grid is very nearly equal to the turn ratio times the primary voltage. This means that if the voltage E_g applied to the winding 7 is constant, the voltage E_{g5} applied to the grid will be very nearly constant. If ME_{g1} = the amplification constant of the device 4, times the voltage applied to the input circuit of this device and the transformation ratio of the auto-transformer $7 = A$,

Resonance occurs when the term of the right hand bracket is zero. Under these conditions

$$C_8 = \frac{L_6}{\omega_0^2 L_6 L_7 - R_4 R_7} \quad (2)$$

If L_6 , L_7 and C_8 are given the proper values, the ratio

$$\frac{E_{g5}}{AME_{g4}}$$

will be practically unity from the resonant frequency to the higher frequencies where the capacity and leakage begin to have an effect. If the circuit is made resonant to the

lowest frequency which it is desired to amplify uniformly and this frequency is assumed to be f_0 , the ratio

$$5 \quad \frac{E_{g5}}{A\bar{M}E_{g4}} = 1 = \frac{\omega_0}{R_4} \frac{L_7}{\left(\frac{L_7}{L_6} + 1 - \frac{1}{\omega_0^2 L_6 C_8} \right) + R_7} \quad (3)$$

Substituting the value of C_8 from Equation (2)

$$10 \quad L_7 = \frac{1}{\omega_0} \left(R_4 + R_7 + \frac{R_4^2 R_7}{\omega_0^2 L_6^2} \right) \quad (4)$$

This equation indicates that there are an infinite number of combinations of L_6 and L_7 which will make

$$\frac{E_{g5}}{A\bar{M}E_{g4}} = 1 \text{ at } \omega_0$$

By selecting another frequency ω_2 about 20 twice ω_0 and making the voltage ratio

$$\frac{E_{g5}}{A\bar{M}E_{g4}}$$

unity, the values of L_6 and L_7 are fixed in 25 such a way as to give substantially unity ratio from ω_0 up. Thus putting

$$\frac{E_{g5}}{A\bar{M}E_{g4}} = 1$$

30 at $\omega = \omega_2$ and C_8 equal to the expression in Equation (2) it follows that

$$35 \quad \omega_2^2 L_7^2 = \left[R_4 \left(\frac{L_7}{L_6} + 1 - \left(\frac{\omega_0}{\omega_2} \right)^2 \frac{L_7}{L_6} + \frac{R_4 R_7}{\omega_2^2 L_6^2} \right) + R_7 \right]^2 + \left[L_7 \left(\frac{\omega_0^2}{\omega_2^2} - 1 \right) \right]^2 \quad (5)$$

Combining Equation (5) with Equation 40 (4) and neglecting small quantities, it follows that

$$45 \quad L_6 = \frac{R_4 \left(\frac{\omega_0^2}{1 - \frac{\omega_0^2}{\omega_2^2}} \right)}{\omega_0 \left(\sqrt{2 - \left(\frac{\omega_0}{\omega_2} \right)^2} - 1 \right)} \quad (6)$$

$$50 \quad L_7 = \omega_0 \left[R_4 + R_7 \left(1 + \left\{ \frac{\sqrt{2 - \left(\frac{\omega_0}{\omega_2} \right)^2} - 1}{1 - \frac{\omega_0^2}{\omega_2^2}} \right\}^2 \right) \right] \quad (7)$$

For $\omega_2 = 2\omega_0$, these equations give the following:

$$55 \quad L_6 = 2.34 \frac{R_4}{\omega_0} = \frac{.373 R_4}{f_0} \quad (8)$$

$$L_7 = \frac{R_4 + 1.18 R_7}{\omega_0} = \frac{.159 R_4 + .188 R_7}{f_0} \quad (9)$$

$$60 \quad C_8 = \frac{1}{\omega_0 (R_4 + .75 R_7)} = \frac{.159}{f_0 (R_4 + .75 R_7)} \quad (10)$$

The relation between the resistance of the device 4, which may be any device having resistance without appreciable inductance, the inductance 6, the capacity 8, and the re-

sistance and reactance of the primary circuit 7 may be expressed as follows: The internal resistance of the device 4 plus the resistance of the primary circuit of the transformer 7 is made substantially equal to each of the reactance of the capacity 8, to the reactance of the primary circuit of transformer 7, and to one half the reactance of the inductance 6 at the lowest frequency in the range of frequencies which it is desired to amplify substantially uniformly.

Taking R_4 as 12000 ohms, R_7 as 1000 ohms, f_0 as 30 cycles, L_6 as 150 henries, L_7 as 70 henries, and C_8 as .415 microfarads, the following values of

are found for different values of frequency:

f	$\frac{E_{g5}}{A\bar{M}E_{g4}}$ (in percent of transformation ratio)
10	8.5
20	68.5
30	100.0
40	101.5
60	100.5
120	100.0

Fig. 2 shows the results determined experimentally with $L_7 = 70$ henries, $L_6 = 37$ henries, $C_8 = 1$ microfarad, $f_0 = 27$ cycles, $R_4 = 5100$, and a 1 to 4 transformer ratio. It will be observed that between 30 and 7000 cycles there is a variation in the ratio

$$\frac{E_{g5}}{A\bar{M}E_{g4}}$$

of only about three percent. This shows that the amplification ratio of the apparatus is substantially constant throughout the entire 103 audio frequency range.

It will be noted that the calculated values are slightly higher than the experimentally determined values at the low frequency end of the curve. This difference is due to the core loss which was not taken into consideration in the calculation. In the apparatus used to secure the data on which the curve is based, the flux density was comparatively high for an interstage transformer. If the flux density is kept low, the core loss effect is practically negligible and the conditions under which substantially constant transformation ratio over a wide range of frequencies is possible can be readily determined from equations (8), (9) and (10).

The embodiment of the invention illustrated and described herein has been selected for the purpose of clearly setting forth the principles involved. It will be apparent, however, that the invention is susceptible of being modified to meet the different conditions encountered in its use and I therefore aim to cover by the appended claims all mod-

ifications within the true spirit and scope of my invention.

What I claim as new and desire to secure by Letters Patent of the United States, is:

5 1. In an audio frequency amplifier, the combination of a space discharge device provided with an anode circuit, an inductance connected in said circuit, a capacity, and a transformer provided with a primary circuit connected to said anode circuit through said capacity, the internal resistance of the space discharge device plus the resistance of the primary circuit of the transformer being substantially equal to each of the react-

10 15 20 25 30 35 40 45 50 55 60 65 70 75 80 85 90 95 100 105 110 115 120 125 130

ance of the capacity, to the reactance of the primary circuit, and to one half the reactance of the inductance at the lowest frequency in the range of audio frequencies which it is desired to amplify substantially uniformly.

2. In an audio frequency amplifier, the combination of a pair of space discharge devices each provided with an input and an output circuit, an inductance connected in the output circuit of one of said devices, a capacity, and a transformer provided with a primary circuit connected to said output circuit through said capacity and with a secondary circuit connected in the input circuit of the other of said devices, the internal resistance of said one of said devices plus that of said primary circuit being substantially equal to the reactance of said capacity, to each of the reactance of said primary circuit, and to one half the reactance of the inductance at the lowest frequency in the range of audio frequencies which it is desired to amplify substantially uniformly.

3. An audio frequency amplifying apparatus including a space discharge device provided with an anode circuit, an inductance connected in said anode circuit, a capacity, and a transformer provided with a primary circuit connected to said anode circuit through said capacity, the magnitude of said inductance in henries being substantially equal to .373 times the resistance of said anode circuit in ohms divided by the lowest audio frequency in cycles per second which it is desired to amplify.

4. An audio frequency amplifying apparatus including a space discharge device provided with an anode circuit, an inductance connected in said anode circuit, a capacity, and a transformer provided with a primary circuit connected to said anode circuit through said capacity, the inductance of said primary circuit in henries being substantially equal to the lowest audio frequency in cycles per second that it is desired to amplify divided into the sum of .159 times the resistance of said anode circuit in ohms and .188 times the resistance of said primary circuit in ohms.

5. An audio frequency amplifying appa-

ratus including a space discharge device provided with an anode circuit, an inductance connected in said anode circuit, a capacity, and a transformer provided with a primary circuit connected to said anode circuit through said capacity, the magnitude of said capacity in microfarads being substantially equal to the quotient obtained by dividing .159 by the product of the lowest audio frequency in cycles per second which it is desired to amplify and the sum of the resistance of said anode circuit in ohms and .75 times the resistance of said primary circuit in ohms.

6. A circuit including a device having resistance and a coupling element including an inductance connected in said circuit and with said device, a transformer winding, and a capacity connected between said inductance and said winding, the magnitude of said inductance in henries being directly proportional to .373 times the resistance of said device in ohms and inversely proportional to the lowest frequency which it is desired to transmit through said element.

7. In an audio frequency amplifier, a device for the transmission of audio frequency currents having a certain internal resistance, an output circuit therefor, a capacity, and an audio frequency transformer having a primary circuit connected with said output circuit through said capacity, the reactances of said capacity and of said primary circuit at the lowest frequency in the range of audio frequencies which it is desired to amplify substantially uniformly being substantially equal to each other and to the internal resistance of said device plus that of the primary circuit.

8. In an audio frequency amplifier, a device for the transmission of audio frequency currents having a certain internal resistance, an output circuit therefor, a capacity, an audio frequency transformer having a primary circuit connected with said output circuit through said capacity, the reactances of said capacity and of said primary circuit at the lowest frequency in the range of audio frequencies which it is desired to amplify substantially uniformly being substantially equal to each other and to the internal resistance of said device plus that of the primary circuit, and means for supplying current to said output circuit including an impedance having a reactance at said lowest audio frequency greater than that of said primary circuit.

9. An audio frequency amplifying apparatus including a space discharge device provided with an anode circuit, an inductance connected in said anode circuit, a capacity, and a transformer provided with a primary circuit connected to said anode circuit through said capacity, the magnitude of said inductance in henries being substantially

equal to .373 times the resistance of said anode circuit in ohms divided by the lowest audio frequency in cycles per second which it is desired to amplify, the inductance of said primary circuit in henries being substantially equal to the lowest audio frequency in cycles per second that it is desired to amplify divided into the sum of .159 times the resistance of said anode circuit in ohms and .188 times the resistance of said primary circuit in ohms, and the magnitude of said capacity in microfarads being substantially equal to the quotient obtained by dividing .159 by the product of the lowest audio frequency in cycles per second which it is desired to amplify and the sum of the resistance of said anode circuit in ohms and .75 times the resistance of said primary circuit in ohms.

In witness whereof, I have hereunto set my hand this 11th day of July, 1927.

Certificate of Correction

Patent No. 1,795,194.

Granted March 3, 1931, to

RUDOLPH A. BIERWIRTH

It is hereby certified that error appears in the printed specification of the above-numbered patent requiring correction as follows: Page 2, line 30, for $\omega = \omega^2$ read $\omega = \omega_2$; same page at the beginning of equation 7 between lines 45 and 50, for $L_7 = \omega_0$ read $L_7 = \frac{1}{\omega_0}$; and that the said Letters Patent should be read with these corrections therein that the same may conform to the record of the case in the Patent Office.

Signed and sealed this 31st day of March, A. D. 1931.

[SEAL.]

M. J. MOORE,
Acting Commissioner of Patents.
